UNITED STATES PATENT OFFICE.

WILLIAM HANFORD KING, OF LITTLE SILVER, NEW JERSEY.

LAND-MARKER.

SPECIFICATION forming part of Letters Patent No. 295,254, dated March 18, 1884.

Application filed April 9, 1883. (No model.)

To all whom it may concern:

Be it known that I, WILLIAM HANFORD KING, of Little Silver, in the county of Monmouth and State of New Jersey, have invented 5 a new and useful Improvement in Land-Markers, of which the following is a full, clear, and exact description.

Reference is to be had to the accompanying drawings, forming part of this specification, in 10 which similar letters of reference indicate corresponding parts in all the figures.

Figure 1, Sheet 1, is a plan view of my improvement, parts being broken away. Fig. 2, Sheet 1, is a front elevation of the same, 15 parts being broken away. Fig. 3, Sheet 1, is a side elevation of the foot for forming the guide-mark, its supporting-rod being shown in section through the line $\alpha\alpha$, Fig. 1. Fig. 4, Sheet 1, is a rear elevation of the same. 20 Fig. 5, Sheet 2, is a side elevation of the improvement, partly in section. Fig. 6, Sheet 2, is a side elevation of the same reversed.

The object of this invention is to facilitate 25 the marking of land for planting and other purposes, and to promote convenience in operating and controlling the markers.

The invention consists in the detailed construction and combination of parts, substantially as hereinafter fully set forth and claimed. 30 A represents the tongue, to which the draft is applied, and which is attached at its rear end to the center of the cross-beam B. The connection between the tongue A and the cross-beam B is strengthened by inclined braces C, attached at their ends to the said tongue and beam.

To the under side of the cross-beam B, upon the opposite sides of and equally distant from its center, is secured by a bolt, D, a plate, E, 40 which has a flange upon the upper side of its forward edge, to rest against the forward edge of the cross-beam B and adapt the said plate to be secured in place by a single bolt. Several holes are formed in the cross-beam B, to receive the bolts D, so that the plates E can be adjusted closer to or farther from the center of the said cross-beam, as may be required.

Upon the ends of the plate E are formed 45 downwardly-projecting arms F, in which are secured the ends of the shaft G, upon which the roller H revolves.

I are small frames, the forward ends of the side bars of which project, are at such a distance apart as to receive between them the 55 roller H, and have eyes in their forward ends to receive the roller-shaft G, so that the rear end of the said frame I will have a free up-and-down movement. The rear ends of the side bars of the frame I project and to and between them is hinged by a long bolt, J, the cross-head K formed upon the shank L of the plow M, so that the said plow can swing forward and back freely, but will be held from lateral movement and from turning to the 65 right or left. This construction allows the plow to be adjusted at any desired pitch.

To the upwardly-projecting end of the plow-shank L is hinged by a bolt, N, the rear end of the bar O, which projects forward over the 70 cross-beam B and rests upon a small roller, P, pivoted to the lugs of a plate, Q, secured to the said cross-beam by the bolt D, that secures the plate E to the said cross-beam. The plow-shank L and the bar O are connected adjustably by a brace-rod, R, the upper end of which passes through a keeper, S, attached to the said bar O, and is secured to the said keeper and bar by a pin, T, as shown in Figs. 1, 5, and 6. Several holes are formed in the upper 80 part of the brace-rod R to receive the pin T, so that the plow can be readily adjusted to have any desired pitch. The lower end of the brace-rod R is slotted to receive the bolt U, that secures it to the plow-shank L, to allow 85 the point of the plow M to swing down close to the rear side of the roller H, as shown in Fig. 6, when the plow is raised from the ground, so that the said plow-point will not be liable to catch upon the obstructions while 90 the machine is being taken from place to place.

To the vertical rear side of a bracket, V, formed upon or secured to the inner rear part of the frame I, is secured by a bolt, W, the lower end of the lever X, by means of which 95 the frame I is operated to raise and lower the plow M. By this construction by loosening the bolt W the upper end of the lever X can be swung inward or outward as the plate E and its attachments are adjusted farther from 100 or closer to the center of the cross-beam B, so that the said upper end of the said lever X can be kept within convenient reach of the driver from his seat. The frame I and its at-

tachments are locked in place when swung upward to raise the plow M from the ground by a latch-hook, Y, hinged to the inner side bar of the frame I, and which engages with a 5 pin, Z, or other suitable catch attached to the inner arm of the plate E. The hook Y is held forward in position to engage automatically with the pin Z when the frame I is raised into position by a spring, a, attached to the frame 10 I, and which bears against the rear end of the said hook Y, as shown in Fig. 6.

To the latch-hook Y is attached the end of a wire, b, the other end of which is attached to an arm of the elbow-lever c. The elbow-lever 15 c is pivoted at its angle to the side of the lower part of the lever X, and to its other end is attached the end of a wire, d, which passes up along the said lever X, and is attached at its other end to an elbow-lever, e, pivoted to the 20 upper part of the said lever X. With this construction, by operating the lever e with the hand that grasps the lever X the hook Y can be readily withdrawn from the pin Z to allow the frame I and its attachments to be 25 lowered.

The plow M is made with a mold-board upon each side, as shown in Fig. 1, and with a foot, M', upon the lower end of the shank L, as shown in Figs. 5 and 6, to slide upon the bottom of the furrow and give steadiness to the plow when at work.

To the lower end of the outer arm, F, of each plate E are hinged the inwardly-projecting ends of the upwardly-projecting flanges formed 35 upon the ends of the foot-plate f, to the rear flange of which is bolted the inner end of a rod, g. The upper side of the outer end of the rod g is beveled, and to it is bolted the inner end of the rod h, the said bevel being such that 40 the said rod h will be level or nearly level.

To the under side of the rod h is secured by a bolt, i, the head of the shank j, which has an upwardly-projecting flange along its forward edge, so that the said shank will be held 45 firmly in place by a single bolt. Several holes are formed in the bar h to receive the bolt i, so that the shank j can be adjusted as the adjustment of the marking-plows M may require.

Upon the lower end of the shank j is formed 50 a foot, k, the lower side of which is rounded, as shown in Fig. 3, so that it will pass over the ground easily, the weight of the shank j and rods g h causing the foot k to make a sufficient mark upon the ground when the soil is 55 loose to serve as a guide to the driver at the next crossing.

l is a short bar, of steel or other suitable material, which is perforated near one end to receive the screw m, by which the said bar l is 60 secured to the rear side of the shank j. When the soil is loose and the foot k will form a sufficient mark, the bar l is secured to the shank j, with its free end upward, so as to be out of contact with the soil, as shown in full 65 lines in Figs. 3 and 4; but when the soil is hard, so that the foot k cannot make a suffi-

cient mark, the bar l is reversed, and is secured to the shank j, with its free end projecting below the foot k, as shown in dotted lines in Figs. 3 and 4, so as to mark the ground as 70 the machine is drawn forward.

The rods g h are strengthened against the draft-strain by the brace-rod n, the outer end of which is bolted to the outer part of the rod h, and its inner end is secured to the forward 75 end flange of the foot-plate f.

To the foot-plate f is secured, or upon it is formed a forwardly-projecting arm, o, having upon its forward end an upwardly-projecting flange to which is pivoted by a bolt, p, the 80 outer end of the bar q. The outer end of the bar q has a short slot formed in it to receive the bolt p, and give the rods g h sufficient play to allow the foot k to accommodate itself to the surface of uneven ground. The inner end 85 of the connecting-bar q passes through the slot in the lower end of the arm r, and is perforated to receive the pin s, which passes through it and through the said slotted arm r. Several holes are formed in the inner end of the 90 bar q to receive the pin s, so that the said bar q can be adjusted to correspond with the adjustment of the marking-plows. The perforated inner parts of the bars q are made thin or are halved to overlap each other within the slot 95 of the arm r, and be secured by the same pin s, so that both bars will be operated at the same time and by the same movement of the arm r. The upper part of the arm r is curved to pass around the tongue A, and its upper 100 end is rigidly attached to the shaft t, which rocks in bearings attached to the upper side of the said tongue A.

To the forward part of the shaft t is rigidly attached the lower end of the upwardly-projecting lever u, so that by operating the said 105 lever u the guide-marker at one side of the machine will be raised and the one upon the other side will be lowered.

With the lever u is connected a spring-lever 110 pawl, v, which engages with a catch-bar, w, attached to the tongue A or to the support for the shaft t, so as to hold the lever u and the mechanism connected with it in any position into which they may be adjusted. With this 115 construction as the machine is drawn forward the plows M open channels to receive seed or for other desired purposes, and the shoe k marks the ground parallel with the channels opened by the plows M, and at such a distance 120 from the outer channel as to be midway between the plows at the next passage of the machine across the field, and thus serve as a guide to the driver in directing the machine to form the channels at uniform distances 125 apart.

The bearings and other parts liable to wear are designed to be protected from sand and dirt by projections formed upon or attached to the frame adjacent to the said parts.

x is a bolt, which projects downward from the tongue A to receive the double-tree, and

which is strengthened against the draft-strain by inclined braces *y*, attached to it and to the tongue-braces *C*, so that by adjusting the bolt *x* or the position of the double-tree upon it 5 the point of draft attachment can be adjusted to take all downdraft from the horses' necks.

If desired, two bolts, *D*, or other suitable appliance, can be used for securing the plate *E* to the cross-beam *B*, to hold the said plate 10 firmly in place.

The mold-boards of the plows *M* can be made in one piece or in two or more pieces, as may be desired.

By connecting one of the bars *q* with the 15 arm *r* below the tongue *A*, and the other with an arm above the tongue, both guide-markers can be raised or lowered at the same time instead of raising and lowering them alternately, as hereinbefore described.

Having thus described my invention, I claim 20 as new and desire to secure by Letters Patent—

1. The combination of the roller-plate flanges *F*; the frame *I*, pivoted to the roller-axle and carrying the plow *M*, whose standard is pivoted to said frame, said frame also 25 having a spring-hook, *Y*, the bar *O*, pivoted to the plow-standard, and with its free end adapted to rest on a roller, *P*, of the beam *B*, and the hand-lever *X*, pivoted upon the frame *I*,

and connected to the bar *O*, said lever having 30 a supplementary lever, *e*, having means for operating the spring-hook *Y*, substantially as and for the purpose set forth.

2. The combination of the roller-plate flanges *F*, the frame *I*, pivoted to the roller-axle and carrying the plow *M*, whose standard is pivoted to said frame, said frame also having a spring-hook, *Y*, the bar *O*, pivoted to the plow-standard, and with its free end adapted to rest on a roller, *P*, the brace *R*, connected 35 to the bar *O*, and having a slot, *U*, in its end connected to the plow-standard, and the hand-lever *X*, pivoted to the frame *I*, and provided with means for operating the spring-hook *Y*, 40 substantially as and for the purpose set forth. 45

3. The combination of the roller-plate flanges *F*, the foot-plate *f*, pivoted to the latter, and having the fixed forwardly-projecting arm *o*, in turn provided with an upwardly-projecting flange having a bolt, *p*, upon which 50 is pivoted the slotted bar *q*, the rods *g h*, and foot *k*, curved bar *r*, shaft *t*, and lever *u*, having a pawl, *v*, and catch-bar *w*, substantially as and for the purpose set forth.

WILLIAM HANFORD KING.
